UNITED STATES PATENT OFFICE

1,969,804

AIRCRAFT CONSTRUCTION

Alphonse F. La Fon, New York, N.Y.

Application March 25, 1931, Serial No. 525,140

Renewed January 13, 1934

15 Claims. (Cl. 244—14)

This invention relates to an improved aircraft of general application, although best fitted for use as a heavier-than-air machine. It comprises lifting elements dependent upon what is known as the Magnus principle, that is, that when a current of air is directed across a rotating drum-like structure, forces will be set up tending to move the structure in a direction perpendicular to the axis of rotation and perpendicular to the direction of the air current.

In its preferred form the invention consists in mounting a plurality of such lifting elements in circular formation around a centrifugal blower in a frame from which a car may be suspended, and in providing means whereby the frame may be tilted with respect to the car and its suspending means in order to vary the direction of motion of the structure as a whole.

Further objects of the invention consist in providing the structure with a directional rudder having a floating connection with the frame in which the lifting elements are mounted; in providing differential gearing through which the blower may be driven by a motor mounted in the suspended car; and in providing the blower with a dome-shaped closure below its air-propelling fans adapted to be brought into a position such as to deflect air outwardly against the lifting elements as a result of an axial movement of the blower to an elevated position, thus providing means for checking the movement of the structure when descending.

In the accompanying drawings illustrating the preferred and a modified form of the invention—

Figure 1 is a side view of the improved aircraft, parts of the mechanism being illustrated in cross-section, the section being taken along the line 1—1 of Fig. 5.

Fig. 2 is a side view of the aircraft drawn to a smaller scale, illustrating the frame and lifting elements as having been shifted to a position such as to produce a component of movement in a forward direction.

Fig. 3 is a front view of the structure illustrated in Figs. 1 and 2.

Fig. 4 is a top view of the frame and car of the machine, certain parts being omitted to disclose underlying structure.

Fig. 5 is a top view of the same structure with the blower and lifting elements in place.

Fig. 6 is a side view of a modified form of lifting element.

Fig. 7 is a view in transverse section of the lifting element illustrated in Fig. 6, the section being taken along the line 7—7.

Fig. 8 is a second view in transverse section of the lifting element illustrated in Fig. 6, the section being taken along the line 8—8.

Referring first to Figs. 1 to 5, inclusive, illustrating the preferred form of the invention, the aircraft comprises a centrifugal blower 20 like structure, mounted for rotation about a vertical axis in a frame comprising rings 21, 22 and 23 (Fig. 4), upper and lower bearings 24, 25 (Fig. 1) for the blower, and connecting braces 26, 27 and 28 (Figs. 1 and 4).

Arranged in circular form around the blower are a plurality of lifting elements 29 (Figs. 1 and 5) adapted to be rotated about their horizontal axes, the respective lifting elements having bearings 30 (Figs. 4 and 5) in the braces 26.

A suitable car 31 (Fig. 1) may be suspended from the frame by hanger rods 32 (Fig. 3) fixedly secured by eyes 33 (Fig. 4) to a cross-shaft 34 pivotally mounted in the ring-like frame structure. This car may be provided with appropriate landing gear conventionally represented as comprising wheels 35 secured to the car by brackets 36 (Figs. 1 and 3).

Within the car may be mounted a suitable motor 37 (Fig. 1) connected by means of gears 38, 39 with a shaft 40 extending lengthwise through a tubular structure 41, the lower end of which may be secured in the car and the upper end of which may be secured by a bracket 42 (Fig. 3) to the cross-bar 34 (Fig. 4). The motor may be provided with the usual controlling means, which need neither be illustrated nor described.

For reasons to be hereinafter made clear, the blower 20 is provided with a shaft comprising two elements, the upper element 43 of which is rotatable in the upper bearing 24 (Fig. 1) and may slide upwardly therein. The lower end of the upper element 43, to which the blower is attached, is in the nature of an internally-threaded nut 44 into which extends the externally-threaded upper end of the lower shaft element 45.

The lower end of the shaft element 45 is extended through the bearing 25 supported from the ring structure 23 by a suitable bracket 46, and terminates with a fixed bevel gear 47 in meshed relationship with a bevel gear 48 rotatably mounted upon the cross-shaft 34 (Fig. 4).

The upper end of the motor shaft 40 (Fig. 1) likewise terminates in a fixed bevel gear 49. A satisfactory form of blower, as conventionally represented in Figs. 1 and 5, may comprise a dished disk or dome-like structure 50 secured to the element 44 of the blower shaft, and, when in its normal position, having its periphery just

clear of the surfaces of the lifting elements 29 at a lever materially below their axes. A plurality of suitable air-propelling vanes 51 may be secured to the dome-like structure in positions such as 5 to cause air to be moved outwardly from their peripheries against the surfaces of the lifting elements 29 so that a portion of the air will be caused to flow over the lifting elements and a portion to flow under the same.

10 The inclination of the threads of the screw-and-nut connection 44, 45 by which the motor shaft is connected with the blower is such as to cause the blower and the shaft 43, 44 to be maintained at the normal elevation indicated in full 15 lines in Fig. 1 whenever the motor is driving the blower.

Any suitable means may be provided for causing the lifting elements 29 to be rotated. This rotation, in order to be effective in accordance with 20 the above-described principle of Magnus, should be such that the upper surface of each element will be moved outwardly or away from the blower. In the form of the invention herein disclosed the rotation is effected by means of the blast of air 25 produced by the blower.

In the form of the invention illustrated in Figs. 1 to 5, inclusive, two of the lifting elements 29, specifically designated 29A, are provided with curved vanes 52 extending lengthwise between 30 end flanges 53. The curvature of these vanes 52 is such as to cause the two elements of which they form a part to be rapidly rotated in the desired direction, indicated by arrows in Fig. 1.

It has been found as a result of experiment that 35 the force set up by the application of the Magnus principle increases very rapidly as the rate of rotation of the drum or cylindrical body is increased.

In geared connection with the lifting elements 40 provided with the vanes 52, which might be regarded as driving elements, are pairs of lifting elements 29B in the form of drums having corrugated surfaces extending from end to end between the flanges 53. These corrugated drums 45 may be regarded as driven elements as compared with the elements 29A.

By suitable step-up gearing 54, 55, the speed of rotation of the driven elements may be increased in any desired ratio, the gearing illustrated in Fig. 5 being such as to cause the driven 50 elements to rotate at five times the speed of the driving elements.

The part of the mechanism thus far described is relied upon as a means of lifting the aircraft 55 vertically from the ground. When the blower is driven by the motor, air is drawn from above into the space within the vanes 51 and thence forced outwardly in every direction and impelled against the drums 29. The reaction of the outwardly-moving air upon the vanes of the driving elements 29A causes them to be rapidly rotated in a direction such that their upper surfaces move outwardly and the driven elements 60 29B will be likewise rotated at a much higher velocity. The effect of the air upon the lifting elements is such as to result in a compression along their under surfaces and a zone of reduced pressure along their upper surfaces, this variation in pressure being materially greater along the 65 surfaces of the driven elements 29B than it is along the surfaces of the driving elements 29A. As a result of these variations in pressure the aircraft will be lifted vertically from the ground at a rate dependent upon the speed of the blower. 70 If desired, any tendency of the machine to ro-

tate as a result of the reactionary forces set up by the rotation of the blower may be prevented by providing one or more deflecting vanes 56 (Figs. 1 and 5) so positioned as to lie in the path of movement of a portion of the air blast produced by the blower. By inclining these vanes in the proper direction, as indicated in Fig. 5, the air passing over them may be caused to neutralize the tendency to rotate the machine set up by the blower. 80

In order that the machine may be driven in a forward direction after it has been elevated by the operation of the blower and the lifting elements, the frame comprising the rings 21, 22, 23, and parts mounted therein are pivotally connected with respect to the hangers 32 and car 31 so that they may be tilted to a position indicated in Fig. 2, after which the forces set up by the lifting elements may be resolved into two components, one tending to prevent the descent 90 of the machine and the other tending to move it in a forward direction. By tilting the frame and the parts mounted therein to varying degrees of inclination, any desired ratio may be established between the lifting component and 100 the forward propelling component.

One means whereby the tilting of the upper part of the structure may be effected by a pilot in the car is illustrated in Figs. 1 and 2. It comprises a pair of cables 57 each of which may be 105 secured at one end to the ring 21 near the front of the machine, thence passed one or more times about a drum 58 rotatably mounted in the car, and then secured at its other end to the ring 21 near the rear of the machine. The drum 58 may 110 be rotated by suitable driving mechanism, herein disclosed as a worm wheel 59 and worm 60, the latter being mounted on a shaft 61 provided with a hand wheel 62 conveniently located for manipulation by the pilot. It will be obvious that a 115 sprocket wheel and chain may be substituted for the drum 58 and cable 57, or any other mechanically equivalent device resorted to as a means of tilting the upper part of the structure. By properly proportioning the distance from the center 120 of the ring frame structure to the center of the drum, the desired degree of tilting may be effected without either materially tightening or loosening the cable 57. Any slight variation may be provided for by including short resilient sections 125 in the form of spiral springs 63 near the ends of the cable, by means of which it may be maintained taut.

Any appropriate means may be provided whereby the direction of movement may be controlled when the upper part of the structure has 130 been tilted to the position indicated in Fig. 2. As herein disclosed, such means comprises a directional rudder 64 pivotally mounted as at 65 upon the end of a light tubular frame comprising 135 curved rods 66 connecting the rudder structure with a pair of small planes or aerofoil elements 67 pivotally mounted at the ends of the rod 34 which traverses the center of the main frame of the machine. This light rudder structure and 140 its frame may therefore swing about the rod 34 so as to float or assume a position such as to afford minimum obstruction against the air as the machine moves in any direction. When being propelled forwardly as indicated in Fig. 2, 145 the air would cause the rudder to trail rearwardly and maintain the rudder frame in a substantially horizontal plane. Were the machine to be moved at an upwardly-inclined angle, the rudder frame would assume a somewhat drooping posi- 150

tion. On the other hand, if the direction of movement were to be changed so as to move along a downwardly-inclined angle, the frame would cause the rudder to be lifted slightly above its point of connection with the frame.

In order that the rudder may not be permitted to swing to a position below the car when the machine is landing, as indicated in broken lines in Fig. 1, and in order that it may not be permitted to swing clear over the structure at the

top and assume an inverted position in front of the machine, any suitable means may be provided to limit its swinging or floating movement. As illustrated in Figs. 1 and 4, such means is indicated as comprising pairs of leaf springs 68 extending forwardly and rearwardly from hangers 69 fixedly secured to the cross-bar 34 at opposite sides of the aerofoil structures 67 as at 70, 71 (Fig. 4).

The position of the rudder 64 may be controlled by cables 72 extending from the ends of arms 73 on the rudder into and through the tubular rudder frame element 66, thence about pulleys 74 (Fig. 5) on the cross-bar 34, and connected at their ends to a pivotally mounted controlling device 75 adapted to be operated by the feet of the pilot.

The planes or aerofoil structures 67 are not relied upon primarily as lifting elements, but will assist in maintaining the rudder structure in a

position such as to set up a minimum resistance against the air when the machine is in motion.

The machine may be elevated, driven in a forward direction, and caused to descend, by properly regulating the speed of the motor and varying the inclination of the upper part of the structure with respect to the car and its hanger. When descending, the frame and parts mounted therein should be returned to their horizontal positions, after which the speed of the motor may be reduced to such an extent that the force of gravity will overcome the lifting force and permit the car to move in a downward direction.

Should the motor fail, so that the blower may no longer be relied upon as a means of creating a

lifting force, special means is provided to prevent the descent of the machine at a rate which would be dangerous. This is best illustrated in Fig. 1.

As there indicated in full lines, the normal position of the blower is such as to direct air from the vanes 51 against the surfaces of the rotatable lifting elements 29. The pitch of the screw-and-nut connection 44, 45 between the motor and the blower, however, is such that if the motor comes to rest and the machine begins to descend, the resistance of the air on the under side of the dome-shaped structure 50 of the blower will cause it to be rotated about its axis and move upwardly along the screw 45 to the position indicated in broken lines in Fig. 1, after which

the air below the blower will be deflected outwardly by the dome-shaped structure and directed against the surfaces of the lifting elements. This outwardly-moving air will cause the lifting elements to continue their rotation and maintain a lifting force opposed to the force of gravity, whereby the undue downward acceleration of the machine will be checked and the machine caused to descend at a speed at which it may alight with safety. As soon as the motor has been repaired

and started, it will cause the screw 45 to advance with respect to the blower and again lower the blower to its normal position.

It will be apparent that the blower when rotated by the motor will serve as an additional

lifting element since all of the air which is driven outwardly by its vanes 51 must be drawn in from the top, the portion which serves as an intake being closed at the bottom by the dome-shaped structure 50. A reduction of air pressure is therefore constantly maintained above the central part of the blower, which is overbalanced by the atmospheric pressure underneath the dome-shaped closure, which accordingly becomes effective as a lifting means.

In Figs. 6, 7 and 8 is illustrated a modified form of lifting element which combines the features of the drums 29B and driving elements 29A of the preferred form illustrated in Fig. 5. The modified form consists of a cylindrical structure having flanges 53' at its ends and driving vanes 52' extending lengthwise throughout a portion only of the length of the structure. The remaining portions 29' are cylindrical drums, which need not necessarily be corrugated as are those of the driven elements 29B of the preferred form. Six of the modified lifting elements like the one illustrated in Figs. 6, 7 and 8 may be substituted for the driving and driven lifting elements 29A, 29B of the preferred form, in which case the gearing may be omitted since each lifting element is provided with its own individual driving vanes. In such modified construction, however, the speed of rotation of the six lifting elements would be substantially equal.

It will be apparent that the car with its load comprising the motor, fuel, pilot, and other equipment would materially exceed in weight the entire superstructure, which may be of relatively light material. The center of gravity of the device as a whole may, therefore, be kept well below the level of the lifting surfaces by suspending the car at a distance below the frame as indicated. The machine will, therefore, be stable at all times.

The invention is not intended to be limited to the forms which have been selected for purposes of illustration, but should be regarded as including variations and modifications thereof within the scope of the appended claims.

What is claimed is:

1. An aircraft comprising a lifting element mounted for rotation about a horizontal axis, a centrifugal blower, rotatable about an axis perpendicular to that of the lifting element for impelling a continuous blast of air in a horizontal direction against its surface from one side, the axis of the lifting element being disposed intermediate the opposite bounding planes of the vanes of the blower, and means for rotating said lifting element in a direction such that its upper surface will move in the direction of movement of the air.

2. An aircraft comprising a lifting element mounted for rotation about a horizontal axis and a centrifugal blower rotatable about an axis perpendicular to that of the lifting element for impelling a continuous blast of air in a horizontal direction against its surface from one side, the axis of the lifting element being disposed intermediate the opposite bounding planes of the vanes of the blower, said lifting element being provided with vanes so disposed as to cause it to be rotated in a direction such that its upper surface will be moved in the direction of movement of the air.

3. An aircraft comprising a plurality of lifting elements disposed in a circular arrangement, each mounted for rotation about a horizontal axis, the various axes being substantially tangent to a common circle, means for impelling air out-

- wardly from within the circle against the inwardly-disposed surfaces of said elements, and means for rotating said elements in directions such that their upper surfaces will move outwardly.
4. An aircraft comprising a plurality of lifting elements disposed in a circular arrangement, each mounted for rotation about a horizontal axis, the various axes being substantially tangent to a common circle, and means for impelling air outwardly from within the circle against the inwardly-disposed surfaces of said elements, said lifting elements being provided with vanes so disposed that they may be rotated by the moving air in directions such that their upper surfaces will be moved outwardly.
5. An aircraft comprising a centrifugal blower mounted for rotation about a vertical axis, a circular series of lifting elements surrounding said blower, each rotatable about a horizontal axis disposed crosswise with respect to the direction of movement of air impelled outwardly by the blower when in motion, and means for rotating said elements in directions such that their upper surfaces will move outwardly.
6. An aircraft comprising a centrifugal blower mounted for rotation about a vertical axis and a circular series of lifting elements surrounding said blower, each rotatable about a horizontal axis disposed crosswise with respect to the direction of movement of air impelled outwardly by the blower when in motion, said lifting elements being provided with vanes so disposed that they may be rotated by the moving air in directions such that their upper surfaces will be moved outwardly.
7. An aircraft, substantially as defined by claim 1, of which the lifting element comprises a rotatable drum and of which the rotating means therefor comprises vanes extending along the drum for a portion of its length only.
8. An aircraft, substantially as defined by claim 3, having a frame as a mounting member for the lifting elements, a car suspended from said frame, and means for tilting the frame with respect to the car and its suspending means.
9. An aircraft, substantially as defined by claim 3, having a frame as a mounting member for the lifting elements, a second frame pivotally connected therewith for swinging movement about a horizontal axis, and a directional rudder pivotally mounted in the second-mentioned frame.
10. An aircraft, substantially as defined by claim 3, of which the lifting elements comprise driving elements and driven elements, the driving elements being provided with vanes so disposed as to cause them to be rotated by the outwardly-impelled air in a direction such that their upper surfaces will be moved outwardly, and the driven elements comprising drums connected with the driving elements by means of step-up gearing adapted to rotate them at a speed greater than that of the driving elements and in a direction such that their upper surfaces will be moved outwardly.
11. An aircraft comprising a frame, a centrifugal blower mounted for rotation in said frame about a vertical axis, said blower being movable axially from a lower to an upper operat-
- ing position, a circular series of lifting elements surrounding said blower, each rotatable about a horizontal axis disposed crosswise with respect to the direction of movement of air impelled outwardly by the blower when rotated while in its lower position, means for rotating said lifting elements in directions such that their upper surfaces will move outwardly, said blower having a dome-shaped closure beneath its air propelled vanes, whereby air deflected outwardly by the under surface of the closure, when the blower is in its uppermost position, may be directed against the inner surfaces of the lifting elements.
12. An aircraft, as defined by claim 11, having a motor and a driving connection between said motor and the blower, said driving connection comprising a nut and screw device having a steep pitch with the inclination of the threads of the screw so disposed with respect to the direction of drive of the motor that a rotation of the blower by the motor will cause the blower to be maintained in its lower position whereas an upward pressure on the dome-shaped under surface of the blower, when the motor is at rest, will cause the blower to be rotated and elevated to its upper position.
13. An aircraft comprising a frame, a centrifugal blower mounted for rotation in said frame about a vertical axis, a circular series of lifting elements surrounding said blower, each rotatable about a horizontal axis disposed crosswise with respect to the direction of movement of air impelled outwardly by the blower when rotated, means for rotating said lifting elements in directions such that their upper surfaces will be moved outwardly, a car suspended from said frame, means for tilting the frame with respect to the car and its suspending means, a motor in said car, and a driving connection between the motor and the blower comprising differential gearing mounted at the pivotal connection between the frame and the suspending means for the car.
14. An aircraft comprising a lifting structure including air-agitating means by and from which air may be forcibly impelled outwardly from within and means lying in the path of the outwardly-impelled air by which it may be deflected, a car suspended from said lifting structure, means for tilting the lifting structure with respect to said car whereby the directive effect of the lifting structure may be varied, and a directional rudder mounted in an arm pivotally connected with said car so as to be free to swing about a horizontal axis.
15. An aircraft comprising a lifting structure including air-agitating means by and from which air may be forcibly impelled outwardly from within and means lying in the path of the outwardly-impelled air by which it may be deflected, a car suspended from said lifting structure, means for tilting the lifting structure with respect to said car whereby the directive effect of the lifting structure may be varied, a motor in the car and a driving connection between the motor and the air-impelling means of the lifting element, said driving connection including differential gearing mounted at the tilting connection between the lifting element and the car.

ALPHONSE F. LA FON.
